UNITED STATES PATENT OFFICE.

HERBERT O. RUSSELL, OF LOS ANGELES, CALIFORNIA.

SEAR AND SEAR RELEASE FOR MACHINE GUNS.

Application filed June 9, 1922. Serial No. 567,114.

To all whom it may concern:

Be it known that I, HERBERT O. RUSSELL, a citizen of the United States, residing at Los Angeles, in the county of Los Angeles and State of California, have invented certain new and useful Improvements in Sears and Sear Releases for Machine Guns, of which the following is a specification.

This invention relates to a sear and sear release mechanism especially designed for use on the bolt of a Browning automatic machine gun. The bolt of the machine gun is slightly modified to hold the sear and sear release.

15 The object of the invention is to provide a means for releasing the firing pin of the gun when a comparatively slight pressure (as compared with the Nelson gear) is exerted on the sear release, without sacrificing 20 any of the mechanical positiveness of the firing mechanism of the gun.

The improved mechanism is intended to be used in connection with an electromechanical trigger motor the direct action of which 25 exerts the releasing pressure on the sear release. The action of the electric trigger motor is very fast and positive and the force exerted by it is comparatively small in order to reduce its size and weight. It is for these 30 reasons that the improved sear and sear release was designed in order that the action thereof might be very positive and require but a small force to actuate.

In the Browning gun, a firing pin is retained in its retracted position by a sear 35 which has a surface sliding on a surface of a pin, the two surfaces extending at ninety degrees from the axis or line of movement of the pin. Since the firing pin spring is of considerable strength, the force required to 40 slide the projection on the sear out of engagement with the projection on the pin, is quite appreciable, and the work done by the sear release slide, which is operated upon by 45 a trigger motor, in moving the sear, is too great for any except a trigger motor of a rather powerful type. It is therefore an object of this invention to provide a firing pin and sear arrangement which may be released 50 in a different manner so as to be operated without any great expenditure of force.

With the above and other objects in view, the invention consists in the novel construction, combination and arrangement herein 55 fully described, illustrated and claimed.

In the accompanying drawings;

Figure 1 is a fragmentary side elevation of the rear portion of the bolt of a machine gun, showing the present invention applied thereto.

Figure 2 is a rear end view of the bolt showing the improved sear and sear release.

Figure 3 is a perspective view looking at the rear end of the bolt.

Figure 4 is a similar view showing the sear and sear release displaced.

Fig. 5 is a vertical section through the rear end of the gun and bolt showing the cooperation of the various parts thereof, and

Fig. 6 is a detail view showing the engaged relation of the sear and firing pin.

Referring to the drawings, 1 designates the bolt of a machine gun which, as is well known, is mounted for reciprocatory movement and which carries the firing pin 2. 75 A firing pin spring 18 is provided which acts on the firing pin to force it to the left when released, see Figs. 1 and 5. The firing pin is provided on its upper side with a projection 3 having a bevelled or cam face 4 80 to engage a depression forming a cam face 4 on a forward projection 5 on the sear 6.

The sear as shown in the drawings is mounted for vertical sliding movement in a groove or guide way 7 in the rear end of the bolt 1 and is formed with ribs 8 along the opposite sides thereof which work in channels 9 in the opposite side walls of the groove 7 thereby insuring accuracy of movement of the sear and retaining the sear in working 90 position. The sear is provided on the rear face thereof with a projecting lug 10 having a cam face 11 designed to cooperate with the cam face 12 of a slidable sear release 13 which operates across the rear face of the 95 sear. The cam face 12 is formed on a projecting lip 14 of the sear release which lip 14 is adapted to engage over the lug 10 and hold down the sear 6 in engagement with the projection 3 on the firing pin thereby 100 holding the firing pin in its retracted position. The cam faces 11 and 12 cooperate to re-set the sear and sear release in the recoil of the bolt. It will be understood that the firing pin travels only a short distance forward after it is released, this distance being sufficiently small so that the lower part of the sear is always touching some part of the upper portion of the firing pin. The spring 17 always presses downwardly upon the 110 sear. After the gun is fired, the sear is cammed upwardly by the firing pin and the

recoil of the gun operates upon the firing pin in the customary manner so that it is moved in relation to the bolt to again assume the position shown in Fig. 1 and so as to permit the spring 17 to force the sear down upon the cam faces of the firing pin as shown in Figs. 1 and 5. When the sear is moved downwardly by the spring 17, the cam faces 11 and 12 cause the slidable sear release 13 to move to the right from the position shown in Fig. 2 and as soon as the sear has reached its position so as to engage the firing pin as shown in Fig. 1, the spring 16 of the sear release operates to move the sear release to the left so that it locks the sear in its down or cocked position.

At one end the sear release 13 has a forwardly projecting extension or spring seat 15 against which bears the outer end of a sear release spring 16, the inner end of which is seated against the base of a recess formed in the bolt to receive said spring. A leaf spring 17 has its free end in engagement with the top of the sear 6 so as to force the sear downwardly into engagement with the firing pin 2, at the same time causing the sear release 13 to be moved horizontally in order that the projection 10 may get under the lip 14 of the sear release.

30 The operation of the mechanism is as follows. Considering the gun to be cocked, with the sear, sear release and firing pin all engaged. The engagement of these parts is retained through the direct action of the firing pin and sear release and coil spring respectively. When the electric trigger motor is energized, the plunger of said motor strikes the end 15 of the sear release, forcing the latter inwardly until the sear becomes disengaged from it. The sear is then cammed by means of the force produced by the firing pin spring, the firing pin going forward immediately. The recoil of the gun automatically brings all of the aforementioned parts back to their original or cocked position to await the next impulse of the plunger on the sear release.

Having thus described my invention, I claim:

50 1. In a machine gun, the combination with the gun bolt, of a sear having a cam faced lug thereon, and a sear release movable across the path of the lug of the sear and having a cam-faced lip to engage and hold

said lug on the sear, said cam faces co-operating to reset the sear, and a firing pin having a cam face to throw the sear when the sear release is operated. 55

2. In a machine gun, the combination with the gun bolt, of a firing pin, a sear having a cam face to engage said pin, guides in said gun bolt for mounting said sear for bodily sliding movement therein, and releasable means for positively holding said sear and pin engaged. 60

3. In a machine gun, the combination with a gun bolt, of a firing pin, a sear, bodily movable in a direction at right angles to the path of movement of said pin, said sear having a cam face to engage said pin, 70 guides in the gun bolt for mounting said sear so as the sear can be cammed by said pin and releasable means for positively holding said sear and pin engaged.

4. In a machine gun, the combination with the gun bolt, of a firing pin, a cam face on said pin, a sear, a guide in said gun bolt for mounting said sear for bodily sliding movement at right angles to the movement of the firing pin, so as the sear may be 80 cammed by the cam face of the firing pin, a sear release for normally positively locking said sear and pin in engagement, and a spring for holding said sear release in engagement with said sear. 85

5. In a machine gun, the combination with the gun bolt, of a firing pin, a cam face on said pin, a sear, a guide for mounting said sear so as the sear may be cammed by the cam face of the firing pin, a sear release for 90 normally positively locking said sear and pin in engagement, and a spring for holding said sear release in engagement with said sear, said sear and sear release being movable along paths ninety degrees apart. 95

6. In a machine gun, the combination with the gun bolt, of a firing pin, a cam face on said pin, a sear, a guide for mounting said sear so as the sear may be cammed by the cam face of the firing pin, a sear release for normally positively locking said sear and pin in engagement, and a spring for holding said sear release in engagement with said sear, said sear, sear release and firing pin all being movable along paths ninety degrees 100 apart in said gun bolt. 105

In testimony whereof I affix my signature.

HERBERT O. RUSSELL.
